CANDLE

Patricia C. Perlmutter, Woodstock, N. Y., assignor to Woodstock Candelier, Woodstock, N. Y., a partnership

Application February 11, 1953, Serial No. 23,554

Term of patent 3½ years

(Cl. D73—1)

To all whom it may concern:

Be it known that I, Patricia C. Perlmutter, a citizen of the United States, residing at Woodstock, county of Ulster, State of New York, have invented a new, original, and ornamental Design for a Candle, of which the following is a specification, reference being had to the accompanying drawing, forming part thereof, wherein:

I claim:

The ornamental design for a candle, as shown.

PATRICIA C. PERLMUTTER.
